FREDRICK RAY MATTESON, OF TAUNTON, MASSACHUSETTS, ASSIGNOR TO FREEMAN-DAUGHADAY COMPANY, OF NORTON, MASSACHUSETTS, A CORPORATION OF MASSACHUSETTS.

SEPARABLE BUTTON.

Application filed September 1, 1925. Serial No. 53,915.

This invention relates to separable buttons, and as applied in the present form relates to a type of separable button that is adapted for use in releasably holding together the opposite ends of cuffs.

It is the object of the invention to provide a simple and reliable construction for a button of this type in which the means for locking the two parts or elements of the button shall be positive and reliable in action, inexpensive to construct and not necessarily dependent upon spring catches for releasably interlocking the parts together.

In general the invention comprises two separable button elements, each comprising a hollow shank with flanges or heads at its opposite ends and loosely mounted coupling members which are positively held in locking position when the parts are assembled which are easily released from such locking position by pressure when it is desired to separate the button elements.

This and other features of the invention will be particularly explained in the following specification and will be defined in the claims hereto annexed.

In the accompanying drawings:

Figure 1 shows a central section of the assembled button with the parts in locking position.

Figure 2 is a similar view with the parts in released position to permit separation of the button elements.

Figure 3 is a detail view of the plunger spring.

Figure 4 is a detail view of the locking or coupling members.

In the practice of this invention according to the form illustrated in the drawings, the socket member of a pair of co-acting button elements comprises a hollow or tubular shank member 1, provided at its inward end (having reference to the assembled button) with an external flange 2, to which is fastened a disk 3 centrally apertured to leave an inwardly projecting ledge or shoulder 3^a, for a purpose presently to be described. The outer head of the socket element, as in the form illustrated in the drawings, comprises a hollow lenticular head consisting of two cupped or bowed disks 4 and 5, whose edges are united together, the shanks being swaged and soldered or other-

wise secured in the central aperture of the disk 4.

The other button element comprises a tubular or hollow shank 6, outwardly turned at its inner end to form a flange member 7, and carrying at its outer end an enlarged head comprising the bowed or concavo-convex disks 8 and 9, secured together with the inner one firmly secured to the outer end of the shank 6.

An intermediate disk 10 is also anchored between the two outside disks 8 and 9 to leave an annular space forming an annular seat for the reception of the outwardly turned flanges or lips 12^a of two approximately semicircular coupling members 12. These coupling members, at their inner or coupling ends, have their side or vertical edges cut away to form V-shaped spaces between them to allow them to rock toward each other at their inner ends.

A plunger 15 is formed with an enlarged head portion 14 and a contracted neck portion 15^a, the head portion having an undercut annular shoulder 14^a to engage the flanged inner end 12^b of the coupling members. The parts are so proportioned that the diameter of the head 14 is too great to allow it to pass into the interior of the coupling members 12 even when they are in expanded position, as shown in Figure 1. The outer end of the plunger 15 is formed with a reduced end 15^c which passes through a central opening in the disk 9 of the head so as to leave a shoulder 15^d.

A cap 16 is secured to this reduced end, 15^c of the plunger, and is provided with an external flange 17 to prevent its movement or withdrawal through the aperture in the disk 9.

Any suitable form of spring may be employed to normally retract the plunger and maintain its shoulder 14^a in engagement with the inner ends of the coupling members 12. In this case I have shown a spider 18 of spring metal whose hub or central portion passes around the reduced portion 15^c of the plunger and is held thereon between the shoulder 15^b and the flange 17 of the cap. The periphery of this spring bears against the interior of the head so as to normally exert an outward but yielding thrust upon the plunger.

To interlock the button members they are placed in axial alignment with the flanges 2 and 7 in juxtaposition, and are pinched together axially with pressure exerted upon 5 the plunger which is thus forced into the position shown in Figure 2, allowing the coupling members 12 to rock inwardly to pass through the interior shoulder 3^a of the socket member since, when the plunger is pushed inwardly, the narrow or tapered neck portion of the plunger comes opposite the flanged inner ends of the coupling members, whose lips 12^b are rounded or bevelled to facilitate such movement by a sort of cam 10 action. Upon releasing the plunger the spring 18 forces the plunger axially outward with reference to its supporting head 9, and the tapered portion of the neck of the plunger positively expands the coupling members 15 into interlocking engagement with the interior lip or ledge 3^a of the socket member, in which position the parts are positively fastened together. Thereafter, to separate the button elements the plunger is pressed inward so that the narrow part of its neck comes opposite the inner ends of the clutch members, allowing them to rock inwardly 20 as the elements are drawn apart.

It will be observed that the action of the 25 clutching or coupling members 12 is entirely positive, both when locking button elements together as well as in unlocking or disengaging. The rounded or bevelled outside edge, at the farther end of the cam lip 12^b, riding against the edge of the ledge or shoulder 3^a, positively forces the coupling members 12 inwardly when the button elements are being snapped together, the axial pressure forcing together the button elements being exerted against the plunger to 30 allow this inward contracting movement of the cam lip on the coupling members or jaws until the lip has passed beyond the ledge or shoulder. The automatic return of the 35 plunger, when pressure thereon is released, forces the cam lip ends of the coupling jaws outward into engagement with the shoulder 3^a, thus positively preventing withdrawal against any pressure that does not disrupt the parts. On the other hand, when the 40 plunger is pressed in to allow release, the cam or bevel surface engagement between the under side of the cam lip and the engaged edge of the shoulder 3^a produces a cam action, as the button elements are pulled apart, that positively forces the coupling elements inward to permit separation.

Either the opposite corners of the shoulder 45 3^a or of the cam lip 12^b may be rounded or bevelled to produce the desired cam action. In this case I have shown all the engaging corners rounded to give a very easy cam action and as the jaws are positively held against contraction by the normally positioned plunger whose bevelled cam surface

adjacent to the stop shoulder 14^a has previously forced them apart, such rounding of the corners does not impair the security of the interlocking engagement. As the locking jaws themselves are neutral as to outward and inward movement, being perfectly free to swing or rock inwardly or outwardly, since they need not be under spring tension, the action is remarkably easy while the engagement is entirely positive.

I believe that I am the first to provide interlocking means for an article of this class in which the locking members themselves are positive in their action both in locking together and releasing, neither of them being under spring tension.

What I claim is:

1. In a separable button the combination of two hollow button elements provided with opposed flanges at their adjacent ends and having tubular shanks connecting the respective flanges with outer enlarged heads, a pair of separate semi-tubular jaws fulcrumed in the enlarged head of the male member to prevent axial play and extend through the shank of said male member into the interior of the shank of the receiving member, said jaws being provided with external lips at their inner ends located to pass beyond and interlockingly engage an interior ledge of the receiving member when the two buttons are assembled, and a spring-actuated jaw-expanding plunger mounted axially in said male member and normally retracted to expand said jaws into locking engagement with ledge, while permitting the jaws to contract inside such ledge when the plunger is pressed inwardly.

2. A separable button embracing in combination two separately interlocked hollow button elements each comprising a tubular shank with an external flange at its inner end and an enlarged head at its outer end, a pair of semi-tubular locking jaws fulcrumed in the head of the male member so as to be held positively against axial displacement therein in either direction, said jaws extending entirely through the shank of the male element and into the shank of the receiving element, an axially disposed jaw-expanding plunger projecting through and beyond both ends of the tubular jaws, a bowed spring mounted in the enlarged head of the male element to have retracting engagement with said plunger to keep the jaws normally expanded, said jaws having, at their inner ends, exterior lips adapted to be expanded by the spring-retracted plunger into positive interlocking engagement with an interior ledge located in the receiving member, whereby the two button elements are positively interlocked against endwise displacement when assembled together.

3. In a separable button, the combination

of two hollow interlocking button elements, each comprising an enlarged outer head, a tubular shank having at its inner end an annular exterior flange, one of said button elements being provided, near its inner end, with an annular inwardly projecting ledge, a pair of semi-tubular locking jaws extending through the shank of the male member and having, at their inner ends, exterior approximately semi-circular locking lips arranged to engage said interior ledge when the elements are assembled, said semi-tubular jaws having their adjacent longitudinal edges cut away to form V-shaped notches when the jaws are assembled to allow them to lock together, and having their outer ends formed with fulcral flanges interlocked with the enlarged head of the male member, and an expanding spring-retracted plunger of circular cross section disposed axially inside said jaws and having a substantially frustro-conical expanding surface engaging the interior end edges of said jaws throughout their total circumference to positively force them against the interlocking ledge, said plunger being formed with an annular recess adjacent to said expanding surface to allow the jaws to contract away from said ledge when the plunger is pressed in. 20 25 30

In witness whereof, I have subscribed the above specification.

FREDRICK RAY MATTESON.
